UNITED STATES PATENT OFFICE.

LESTER C. RAU, OF CINCINNATI, OHIO.

DESIGN FOR A WINDOW-DISPLAY SIGN.

Application filed February 24, 1928. Serial No. 25,559. Term of patent 14 years.

To all whom it may concern:

Be it known that I, LESTER C. RAU, a citizen of the United States, residing at Cincinnati, in the county of Hamilton and State of Ohio, have invented a new, original, and ornamental Design for Window-Display Signs, of which the following is a specification, reference being had to the accompanying drawing, forming part thereof.

Fig. 1 is a front elevation of a window display sign, showing my new design and Fig. 2 is a side elevation of the same.

I claim:

The ornamental design for a window display sign, as shown.

LESTER C. RAU.
